(57) **CLAIM**

The ornamental design for a phone holder, as shown and described.

DESCRIPTION

FIG. 1 is a bottom and right side perspective view of a phone holder with a top portion connected to the base by a flexible cord in a hanging position showing my new design;

FIG. 2 is a bottom and right side perspective view thereof showing the top portion in an extended position;

FIG. 3 is a bottom and right side perspective view thereof showing the holding of a phone;

FIG. 4 is a front elevation view of FIG. 2;

FIG. 5 is a rear elevation view thereof;

FIG. 6 is a left side elevation view thereof;

FIG. 7 is a right side elevation view thereof;

FIG. 8 is a top plan view thereof;

FIG. 9 is a bottom plan view thereof;

FIG. 10 is a front and right side perspective view thereof;

FIG. 11 is a front and right side perspective view thereof showing the holding of a phone;

FIG. 12 is a front and right side perspective view thereof showing the holding of a phone and the attachment to a vertical pole; and,

FIG. 13 is a front and right side perspective view thereof showing the holding of a phone and the attachment to a horizontal pole.

The uniformly spaced diagonal hatching shown on the flexible portion of the phone holder represents a contrast in appearance only and does not represent any particular color, material, texture, or finish.

The broken lines showing a phone in FIGS. 3, 11, 12, and 13 depict environment that forms no part of the claimed design. The broken lines showing a pole in FIGS. 12 and 13 depict environment that forms no part of the claimed design.
